UNITED STATES PATENT OFFICE.

WILLIAM H. MCKISSICK, OF TULSA, OKLAHOMA.

SAFETY SHEAVE BLOCK.

Application filed May 27, 1926. Serial No. 112,044.

This invention relates to new and useful improvements in safety sheave blocks.

The object of the invention is to provide a block with a housing having one or both 5 sides hinged to swing open for removing and replacing the lines.

A further object of the invention is to provide a block housing with guard flanges separated when one of the sides is opened.

10 Another object of the invention is to provide in connection with said swinging side, spacer blocks co-acting with the said flanges at the upper ends of the housing to separate the lines of cable and to prevent the hands 15 of the workman being drawn into the top of the block.

A construction designed to carry out the invention will be hereinafter described together with other features of the invention.

20 The invention will be more readily understood from a reading of the following specification and by reference to the accompanying drawings, in which an example of the invention is shown and wherein:

25 Fig. 1 is a side elevation of a sheave block constructed in accordance with my invention,

Fig. 2 is a transverse vertical sectional view taken on the line 2—2 of Fig. 1, and

30 Fig. 3 is a horizontal cross-sectional view taken on the line 3—3 of Fig. 1.

In the drawings the numeral 10 designates a central vertical partition plate from which upright side bars 11 are spaced by spacer 35 members or blocks 12 welded or otherwise secured thereto. Side or cover plates 13 are hinged at their upper ends at 13' to the side bars. The parts 10, 11, 12 and 13 form a housing. A becket bolt 14 passes through 40 the upper ends of the parts 10 and 11 and an upper becket 15 has its ears pivoted on said bolt on each side of the partition between the side bars.

A lower becket bolt 16 passes through the 45 lower end of the housing and a lower becket is pivoted thereon. This becket comprises a hook member 17 and a keeper member 20, the latter having spaced ears 19 at its lower end receiving an ear 18 on the end of the bill 50 of the hook member. A locking bolt 21 is passed through the ears. When it is desired to thread the lower becket the bolt 21 is withdrawn and the keeper member 20 is 55 swung to one side.

55 The side plates 13 are each provided with inwardly directed longitudinal flanges 22

along each vertical edge. The adjacent edges of these flanges, as is shown in Fig. 3, are slightly spaced apart, but the flanges are substantially aligned. These flanges co-acting 60 with the spacer blocks 12 cover the lines of the cable and protect the workman's hands. A sheave bolt 23 is mounted transversely in the bars 11 and the plate 10. Sheaves 24 are mounted in said bolt on each 65 side of the plate 10 and between the bars 11. The blocks 12 overhang the sheaves. The side plates 13 have openings 25 for the bolt 23 so that said plates are free to swing when 70 released.

It will be seen that the lower becket bolt 16 passes through the lower ends of the side plates 13 and when it is desired to open one or both of said plates the bolt must be removed. When one of the plates is swung 75 outward on its hinge 13' its flanges 22 are displaced from the flanges of the other plate and the block thus opened for the removal or replacement of the cable lines. It is 80 pointed out that only one of the plates may be hinged and the other suitably fastened to its side bar, if desired. Handles 27 may be provided on the side plates.

Various changes in the size and shape of 85 the different parts, as well as modifications and alterations, may be made within the scope of the claims.

What I claim is:

1. In a safety sheave block, a support, a becket from which the support is suspended, 90 side plates mounted on the support, a sheave journaled on the support and having its vertical sides between the plates, and flanges along the plates directed transversely of the sheave, the vertical outer edges of the flanges 95 of one plate being contiguous to the outer free edges of the flanges of the other plate, said flanges forming guards for the groove of the sheave, one of said plates being hinged to swing outwardly from the vertical side of the sheave to separate the flanges. 100

2. In a safety sheave block, a support, a becket from which the support is suspended, side plates mounted on the support, a sheave journaled on the support and having its vertical sides between the plates, flanges along the plates directed transversely of the sheave, the vertical outer edges of the flanges 105 of one plate being contiguous to the outer free edges of the flanges of the other plate, said flanges forming guards for the groove 110 of the sheave, one of said plates being hinged

to swing outwardly from the vertical side of the sheave to separate the flanges, and a spacer member at the center of the upper end of the support overhanging the sheave 5 relatively between the plates, and on each side of the vertical axis of the sheave, the ends of the spacer member being adjacent the upper ends of the guard flanges.

3. In a safety sheave block, a pair of vertical side bars, a spacer block between said side bars, upper and lower becket pivoted to the ends of said side bars, side plates mounted on said side bars, a sheave journaled between said side bars and said plates, 10 and longitudinal guard flanges along the plates directed transversely of the sheaves, one of said plates being hinged to one of the side bars for swinging outwardly at an angle to the vertical side of the sheave to 15

separate its flanges from the flanges of the other plate.

4. In a safety sheave block, vertical side bars, a vertical partition between said bars, spacer blocks at the upper ends of the bars and the partition, side plates mounted on the bars on each side of said partition, sheaves journaled between the side bars and plates and on each side of the partition, an upper becket from which the side bars are suspended, and vertical guard flanges along the vertical edges of each plate directed transversely of the sheaves with their free edges contiguous, one of said side plates being hinged to one of the side bars for swinging outwardly to separate its flanges from the flanges of the other plate.

In testimony whereof I affix my signature.

WILLIAM H. McKISSICK.
